TIMING INSTRUMENT

Leonard P. Dorsett, Bethlehem, Pa., assignor
The Standard Electric Time Company, Springfield, Mass., a corporation

Application January 28, 1935, Serial No. 3,701

10 Claims. (Cl. 161—15)

This invention relates to improvements in timing instruments, and more particularly to timing instruments used to accurately measure time within a small fraction of a second.

5 One object of this invention is to provide an improved timing instrument which shall have greater accuracy than mechanically-acting timing instruments heretofore known.

Another object of this invention is to provide 10 an improved timing instrument formed of simple elements, readily manufactured and readily assembled to produce a durable, efficient construction at minimum cost.

With the above and other objects in view, this 15 invention includes all improvements over the prior art which are disclosed in this application.

In the accompanying drawings, in which one way of carrying out the invention is shown for 20 illustrative purposes:

20 Fig. 1 is a front elevation illustrating one embodiment of the invention;

Fig. 2 is a sectional view on line 2—2 of Fig. 1, without cutting away the motor construction;

Fig. 3 is a view similar to Fig. 2, most of the 25 parts being in elevation, with the electromagnet energized and the clutch-members engaged;

Fig. 4 is a detached perspective view of the 30 driven clutch-member; and

Fig. 5 is a similar view of the clutch-fork.

35 In the description and claims, the various parts are identified by specific names for convenience, but they are intended to be as generic in their application as the prior art will permit.

Referring to the drawings, 10 and 11 are front 40 and rear main movement-plates, and 12 is a supplemental rear movement-plate. Movement-plates 10 and 11 are connected together by the three pillars 13, and rear movement-plate 11 is connected to the supplemental rear movement-plate 12 by the two pillars 14. Pillar 15 extends between and interconnects the plates 10 and 12.

45 Rotatably journaled at 16 and 17 in the movement-plates 10 and 11, is a time-element or time-arbor or time-shaft 18, on which are mounted a pair of clutch-members or elements 19 and 20. Clutch-member 19 is rotatably mounted on the shaft 18 and has formed on the clutch-member or secured thereto a spur-gear 21 which meshes with a companion spur-gear 22 of the same size and number of teeth, which spur-gear 22 is firmly secured to an arbor or shaft 23, which is journaled in the movement-plates 10 and 11. The shaft 23 is normally driven at constant speed by a suitable motor such, for example, 50 as the synchronous motor 24 which is connected

to the rear movement-plate 11 in any suitable way, as by the supporting studs 25. Suitable reduction-gearing of known form may be used with the motor, to preferably drive the gears 22 and 21 at a speed of one revolution per second, 5 although other speeds may be provided if so desired.

The clutch-member 20 has secured thereto or formed thereon, an arm 26 provided with a slot 7 and provided at its opposite end with a counterweight 28.

Gear 29 is firmly secured on the arbor 18 and rests against the front face of the front movement-plate 10. In securing the bushing 30 to the shaft 18, the bushing 30 and the gear 29 are 15 pressed toward each other with a concavo-convex spring-washer 31, which may be made of spring brass or bronze, between the bushing 30 and the movement-plate 10 to bring about suitable friction between the bushing 30 and the 20 washer and the plate 10, for a purpose to be later described, whereupon the bushing is firmly secured in its position upon the shaft 18 by means of the two screws 32.

Riveted to or otherwise secured to or formed 25 with the bushing 30 is a heart-shaped resetting-cam 33, which has a projecting-pin 34 which engages in the slot 27, so as to cause the clutch-member 20 and bushing 30 to rotate in unison with the shaft 18, but to permit longitudinal sliding movement of the clutch-member 20 on the shaft 18. 30

The gear 29 is connected, through the medium of dial-work or gearing (not shown), with the gear 98, which gear 98 carries lugs 99, 100, to 35 which lugs is secured a spring-wire 101 which frictionally engages in the groove 102 of the hub 103 of the heart-shaped cam 97, which cam 97 is secured to the time-sleeve 35 by means of a key 104, to rotate the time-sleeve 35 at any 40 desired ratio compared to the time-shaft or arbor 18. The time-shaft 18, together with the pointer 36 secured thereto, may, for example, rotate one complete revolution in a second, while the time-sleeve 35 and the pointer 37 secured thereto may 45 be made to have one complete rotation in one minute.

The clutch-members 19 and 20 respectively have clutch-facing elements 38 and 39 preferably formed of organ-bellows leather, and each 50 leather preferably of about .015" thickness. The leather facings 38 and 39 may be secured to the clutch-members 19 and 20 by cementing thereto with shellac or any other suitable material, and preferably have the clutch-faces of the facings 55

38 and 39, which are adjacent each other, formed of the hair-side of the leather. These facings 38 and 39 of organ-bellows leather are characterized by being soft and compressible, and give 5 good clutching action with light forces. This leather is also pre-treated so that it will not absorb oil.

The hub 40 of the clutch-member 19 has its left-end central annular portion 41 adapted to 10 bear against the rear movement-plate 11, but has the larger-diametered annular portion 42 cut back so as to be out of contact with the movement-plate 11. Owing to this construction, the clutch-member 19 possesses self-aligning 15 characteristics. Thus, when the clutch-member 20 is forced toward the clutch-member 19, the latter is able to rock to the necessary degree to perfectly align the clutch-faces of the facings 38 and 39, so as to bring about perfectly uniform pressure and clutching action between the clutch parts.

The hub 43 of the clutch-member 20 has an annular groove 44 in which engage the opposite fingers or prongs 45 which may be formed as 25 part of a U-shaped piece of piano wire secured by solder 46 or otherwise to the bar or lever 47, to thus form clutch-moving means in the form of a clutch-actuating arm or clutch-arm or fork 48, which is pivoted at 49 to the upstanding ears 30 50 formed as part of the U-bracket 51 which is secured by rivets 52 or otherwise to the armature or clutch-arm actuating-member or bar 53.

The stud 54 is secured to the upper end of the member 53 by means of reduced threaded portion 55, screwed into the arm 53 or otherwise. The stud 54 has an oppositely-extending reduced shank 56 provided with a hole 57, through which extends a cotter-pin 58.

A yieldable member or spring 59 presses at 40 one end against the cotter-pin 58 and at the other end against a washer 60 to yieldably clamp the clutch-actuating arm 48 between the washer 60 and the enlarged portion 61 of the stud 54. The armature or clutch-arm actuating-member 45 53 has slots 62 at its opposite sides to contain the projecting hinge-fingers 63 of the U-shaped supporting-bracket 64.

The locking-bracket 65 has an enlarged head 66 adapted to be inserted through the slot 67 50 in the member 53 in order to assemble the parts together and permit of the head 66 being brought in position (Fig. 1) to prevent the member 53 from falling off its hinged connection with the hinge-fingers 63. The bracket 65 has a pair of 55 elongated slots 68 through which extend a pair of screws 69 which screw into the lower arm of the bracket 64, and by means of the split lock-washers 70, firmly secure the two brackets 64 and 65 together with the enlarged head 66 in 60 proper adjusted position. The bracket 65 at one end has an angular bend 71 provided with notches 72 at its opposite sides, in which is anchored a ring-portion 73 of a coil of a yieldable member in the form of a coil-spring 74, which has a 65 ring 75 at its opposite end anchored in an aperture 76 in the end of a screw-threaded bolt 77, which passes freely through a hole in the lower portion of the member 53 and carries a nut 78 threaded on the bolt 77 to draw the coil-spring 70 74 into any desired degree of tension adjustment. The nut 78 is locked in any desired position of adjustment by virtue of its engagement by the pressed-out lugs 79. The said nut 78 may be turned to adjust the tension of the 75 spring 74 by drawing it axially outwardly beyond

the said lugs 79. After the nut has been turned as desired, it may be released for inward axial movement, whereupon the hexagon sides of the nut snap down between the lugs and can be left thus locked in any desired adjusted position. 5

A screw 80 extends through the plate 12 and threadedly engages in the core 81 of the electromagnet 82, to clamp the electromagnet and bracket 64 firmly to the plate 12. The core 81 of the electromagnet may be provided with a shading-coil 83 of non-magnetic material, which has portions 84 and 85 extending through slots in the end of the core which is adjacent the armature 53 which latter is of magnetic material and acts as an armature for the electromagnet. The portions 84 and 85 together with the end-portions 86 and 87 of the shading-coil, form a complete circuit. This shading-coil acts in a known manner to substantially double the number of pulls of an alternating current on the armature-member 53, to thus minimize the tendency of the apparatus to produce noise or humming. 15

The electromagnet 82 has terminals 88 and 89 which may, if desired, be connected to the same source of electrical supply 90 and 91 as supplies current to the motor 24, or, if desired, a separate source of current may be utilized for the electromagnet 82. The switch 92 serves for energizing the electromagnet at such times as is desired. 25

The resetting heart-shaped cam 33 is engaged by a roller 93 rotatably mounted on a stud 94 secured to the plunger 95 which is mounted for up-and-down sliding action (Fig. 1) and is normally held in its up position by a spring (not shown). The plunger 95 may carry a usual operating-button (not shown) on its upper end for hand engagement to press the plunger 95 down to cause the roller 93 to press against and rotate the cam 33 until the low point 96 of the latter comes beneath the roller 93 to thereupon bring the pointer 40 36 to its central or zero position.

The time-sleeve 35 also has secured thereto a similar heart-shaped cam 97 which will be actuated in a similar manner by a roller similar to the roller 93, carried by an arm interconnected with the plunger 95, so that when the latter is pushed down, it also rotates the resetting-cam 97 to properly reset the pointer 37 to its original position. 45

In operation, the motor 24 normally drives the gears 22 and 21 and clutch-member 19 at constant speed, for example, one revolution per second. Upon desiring to count or time anything, the switch 92 is closed to thereupon energize the electromagnet 82, which attracts its armature-member 53 and causes the clutch-fork 48 to move the clutch-member 20 into engagement with the clutch-member 19, to thereupon start the pointers 36 and 37 to travel through their timing or counting movement. 50

Upon opening the circuit 92 to break the circuit to the electromagnet 82, the spring 74 pulls the armature-member 53 away from the electromagnet and causes the enlarged portion 61 of the stud 54 to throw the clutch-fork 48 to the right 65 (Fig. 2) to thus unclutch the clutch-members 19 and 20. When this unclutching action takes place, the concavo-convex spring-washer 31, by virtue of its friction, causes the bushing 30 and the arbor 18 to very promptly stop, thus leaving the 70 pointers 36 and 37 in their counting or time-indicating position. The pointer 36, for example, may indicate divisions on a large outer circle divided up to indicate hundredths of a second, while the pointer 37, for example, passes over an inner 75

circle having sixty divisions to indicate seconds.

Upon closing the switch 92, there is, as is well known, a certain lag in the action of the electromagnet 82, so that the pointers 36 and 37 do not 5 instantly begin their travel. I have found, however, that by providing the spring 74 with an adjustable construction such as 77, 78, the speed of opening of the clutch-members can be so adjusted that the overrun of the pointers 36 and 37 10 will substantially exactly equal the lag or under-run of the pointers in starting. This can be done with such great accuracy that in practice, devices constructed in accordance with this invention are able to operate to indicate time intervals to an 15 accuracy of 1/600 of a second.

It will be observed that when the electromagnet pulls the armature-member 53, the spring 59 prevents the violent powerful thrust action of the electromagnet from acting directly upon the 20 clutch-member 20, but instead, provides a cushioned or yielding action whereby the clutch-fork 48 is caused to push the clutch-member 20 into clutching engagement with the clutch-member 19 by a yielding action due to the spring 59.

25 After the position of the pointers 36 and 37 has been observed so as to measure or count any given thing, the plunger 95 is pushed down against the action of its spring to act upon the heart-shaped cams 33 and 97 to return the pointers 36 and 37 30 to their original position ready for the next time it is desired to close the switch 92 to again measure or count anything.

The invention may be carried out in other specific ways than that herein set forth without departing from the spirit and essential characteristics of the invention, and the present embodiment is therefore to be considered in all respects as illustrative and not restrictive, and all changes 40 coming within the meaning and equivalency range of the appended claims are intended to be embraced therein.

I claim:

1. A timing instrument including: a time-element; a normally-driven, constant-speed motor; 45 clutch members to operatively connect said time-element and motor together; a clutch-moving means for relatively moving said clutch-members to clutched and unclutched positions; yieldable means acting on said clutch-moving means and 50 tending to relatively move said clutch-members to one of said positions; clutch-actuating means to relatively move said clutch-members to the other of said positions against the action of said yieldable means; and adjustable means to adjust the yieldable action of said yieldable means to vary the speed of actuation of the clutch by said yieldable means to equalize the underrun and overrun of said time-element.

2. A timing instrument including: a time-element; a normally-driven, constant-speed motor; clutch-members to operatively connect said time-element and motor together; a clutch-arm for relatively moving said clutch-members to clutched and unclutched positions; yieldable means acting 60 on said clutch-arm and tending to relatively move said clutch-members to unclutched position; clutch-actuating means to relatively move said clutch-members to clutched position against the action of said yieldable means; and adjustable 65 means to adjust the yieldable action of said yieldable means to vary the speed of actuation of the clutch by said yieldable means to equalize the underrun and overrun of said time-element.

3. A timing instrument including: a time-element; a normally-driven, constant-speed mo-

tor; clutch-members to operatively connect said time-element and motor together; a pivoted clutch-arm for relatively moving said clutch-members to clutched and unclutched positions; yieldable means acting on said pivoted clutch-arm and tending to relatively move said clutch-members to unclutched position; electromagnetic clutch-actuating means to relatively move said clutch-members to clutched position against the action of said yieldable means; and adjustable 10 means to adjust the yieldable action of said yieldable means to vary the speed of actuation of the clutch by said yieldable means to equalize the underrun and overrun of said time-element.

4. A timing instrument including: a time-element; a normally-driven, constant-speed motor; friction, clutch-members to operatively connect said time-element and motor together; soft, readily-compressible friction-facing between said clutch-members; a clutch-moving means for relatively moving said clutch-members to clutched and unclutched positions; yieldable means acting on said clutch-moving means and tending to relatively move said clutch-members to one of said positions; clutch-actuating means to relatively move said clutch-members to the other of said positions against the action of said yieldable means; and adjustable means to adjust the yieldable action of said yieldable means to vary the speed of actuation of the clutch by said 30 yieldable means to equalize the underrun and overrun of said time-element.

5. A timing instrument including: a time-element; a normally-driven, constant-speed motor; friction clutch-members to operatively connect said time-element and motor together; said bellows leather friction-facing between said clutch-members; a clutch-moving means for relatively moving said clutch-members to clutched and unclutched positions; yieldable means acting on said clutch-moving means and tending to relatively move said clutch-members to one of said positions; clutch-actuating means to relatively move said clutch-members to one of said said positions against the action of said yieldable means; and adjustable means to adjust the yieldable action of said yieldable means to vary the speed of actuation of the clutch by said yieldable means to equalize the underrun and overrun of said time-element.

6. A timing instrument including: a time-element; a normally-driven, constant-speed motor; friction clutch-members to operatively connect said time-element and motor together; said clutch-members being mounted to have relative 55 rocking movement to automatically provide self-alignment between the clutch-faces of the clutch-members when they are brought into clutching engagement; a clutch-moving means for relatively moving said clutch-members to clutched and unclutched positions; yieldable means acting on said clutch-moving means and tending to relatively move said clutch-members to one of said positions; clutch-actuating means to relatively move said clutch-members to the other of said 60 positions against the action of said yieldable means; and adjustable means to adjust the yieldable action of said yieldable means to vary the speed of actuation of the clutch by said yieldable means to equalize the underrun and overrun of 65 said time-element.

7. A timing instrument including: a time-element; a normally-driven, constant-speed motor; clutch-members to operatively connect said time-element and motor together; a pivoted clutch-

arm for relatively moving said clutch-members to clutched and unclutched positions; a pivoted clutch-arm-actuating-member for moving said clutch-arm to relatively move said clutch-members to clutched and unclutched positions; yieldable means acting on said clutch-arm-actuating-member and tending to relatively move said clutch-members to unclutched position; clutch-actuating means acting on said clutch-arm-actuating-member to relatively move said clutch-members to clutched position against the action of said yieldable means; and adjustable means to adjust the yieldable action of said yieldable means to vary the speed of actuation of the clutch by said yieldable means to equalize the underrun and overrun of said time-element.

8. A timing instrument including: a time-element; a normally-driven, constant-speed motor; clutch-members to operatively connect said time-element and motor together; a pivoted clutch-arm for relatively moving said clutch-members to clutched and unclutched positions; a pivoted clutch-arm-actuating-armature for moving said clutch-arm to relatively move said clutch-members to clutched and unclutched positions; yieldable means acting on said clutch-arm-actuating-member and tending to relatively move said clutch-members to unclutched position; electromagnetic clutch-actuating means acting on said clutch-arm-actuating-armature to relatively move said clutch-members to clutched position against the action of said yieldable means; and adjustable means to adjust the yieldable action of said yieldable means to vary the speed of actuation of the clutch by said yieldable means to equalize the underrun and overrun of said time-element.

9. A timing instrument including: a time-element; a normally-driven, constant-speed motor; clutch-members to operatively connect said time-element and motor together; a pivoted clutch-arm for relatively moving said clutch-members to

clutched and unclutched positions; a pivoted clutch-arm-actuating-member for moving said clutch-arm to relatively move said clutch-members to clutched and unclutched positions, the connections between said clutch-arm-actuating-member and said clutch-members including first yieldable means; second yieldable means acting on said clutch-arm-actuating-member and tending to relatively move said clutch-members to unclutched position; clutch-actuating means acting on said clutch-arm-actuating-member to relatively move said clutch-members to clutched position against the action of said second yieldable means; and adjustable means to adjust the yieldable action of said second yieldable means to vary the speed of actuation of the clutch by said second yieldable means to equalize the underrun and overrun of said time-element.

10. A timing instrument including: a time-element; a normally-driven, constant-speed motor; clutch-members to operatively connect said time-element and motor together; a pivoted clutch-arm for relatively moving said clutch-members to clutched and unclutched positions; a pivoted clutch-arm-actuating-armature for moving said clutch-arm to relatively move said clutch-members to clutched and unclutched positions, the connections between said clutch-arm-actuating-armature and said clutch-members including first yieldable means; second yieldable means acting on said clutch-arm-actuating-member and tending to relatively move said clutch-members to unclutched position; electromagnetic clutch-actuating means acting on said clutch-arm-actuating-armature to relatively move said clutch-members to clutched position against the action of said second yieldable means; and adjustable means to adjust the yieldable action of said second yieldable means to vary the speed of actuation of the clutch by said second yieldable means to equalize the underrun and overrun of said time-element.

LEONARD P. DORSETT.
